ELECTRIC CIRCUIT BREAKER

John A. Oppel, Aldan, Pa., assignor to General Electric Company, a corporation of New York

Application November 21, 1957, Serial No. 697,878

6 Claims. (Cl. 307—136)

This invention relates to an electric circuit breaker of the type that is provided with voltage-controlling impedance means shunting its main contacts and, more particularly, relates to an improved switching arrangement for interrupting the current flowing through said impedance means after said main contacts have been opened.

For controlling the voltage developed across the main contacts of a circuit breaker during a circuit-interrupting operation, it has been customary to shunt these contacts with an impedance through which current is transferred when the main contacts are opened to interrupt the circuit. For interrupting the current through the impedance, there is customarily provided a switch which opens after the main contacts have been opened.

In order for the impedance consistently to carry out its intended function during the interrupting process, it is important that its switch always be opened at a precisely-controlled predetermined time interval after the main contacts part.

Most prior arrangements for operating such a switch have not been capable of controlling this time interval with the desired degree of precision and consistency. For example, the usual fluid-controlled operating arrangements have been subject to inconsistencies as a result of variations in the pressure and temperature of the operating fluid. Direct mechanical couplings between the impedance switch and the main contacts have sometimes been used, but prior couplings of this nature have been subject to certain disadvantages. For example, they generally do not lend themselves to providing a long enough time delay and, in many cases, do not readily lend themselves to closing the switch and main contacts in the desired timed sequence during closing of the circuit breaker. In this regard, it is desirable that closing of the impedance switch be delayed until relatively late in the closing stroke for the main contacts, thus providing for reduced heating of the impedance as a result of current flowing therethrough prior to closure of the main contacts.

Accordingly, it is an object of my invention to provide, in a circuit breaker of this general type, improved operating means for consistently opening an impedance switch at a precisely-controlled predetermined time interval after the main contacts part.

Another object is to construct the switch-operating means in such a manner that it is capable of providing an accurate time delay of a relatively great duration and is also capable, during a closing operation, of delaying closing of the impedance switch until relatively late in the closing stroke of the main contacts.

In carrying out my invention in one form, I provide a circuit breaker which has its main contacts shunted by an impedance. Connected in series with the impedance and in shunt with the main contacts, separable auxiliary contacts are provided. A common actuating member is provided for a movable one of the main contacts and a movable one of the auxiliary contacts.

2

Means connecting the actuating member and the movable main contact causes the main contacts to part in response to opening movement of the actuating member. A co-ordinating member connected between the actuating member and an auxiliary contact-operating spring is arranged to effect charging of the spring in response to initial opening movement of the actuating member. A latch is provided to block discharge of the spring during such initial opening movement, but, at a selected point thereafter, means controlled by the coordinating member acts to release the latch, thus allowing the spring to discharge. A lost-motion connection provided between the spring and the movable auxiliary contact allows initial discharge of the spring to take place without affecting the then-closed position of the movable auxiliary contact, but, at a selected point thereafter, this connection transmits forces from the spring to the movable auxiliary contact, and such forces open the auxiliary contacts. Due to the intentional time delay in tripping the latch and the intentional time delay resulting from the lost-motion connection, the auxiliary contacts part substantially after the main contacts have parted.

For a better understanding of my invention, reference may be had to the following specification taken in connection with the accompanying drawings, wherein:

Fig. 1 is a side elevational view, partially in section, showing a circuit breaker embodying my invention. The circuit breaker is depicted in the closed position.

Fig. 2 is a sectional view taken along the line 2—2 of Fig. 1.

Fig. 3 is a view similar to that of Fig. 2 except showing the parts of Fig. 2 at an instant during a circuit breaker-opening operation.

Fig. 4 is a view partially in section taken along the line 4—4 of Fig. 1.

Referring now to Fig. 1, the circuit breaker shown therein is of the general type disclosed and claimed in Patent No. 2,783,338—Beatty, assigned to the assignee of the present invention. This circuit breaker comprises an enclosed interrupting chamber 11 defined, in part, by a metallic casing 12 which is filled with pressurized arc-extinguishing gas.

A pair of elongated conductive studs 15 and 20 project into the casing 12 from diametrically-opposed points, and each of these studs carries a suitable stationary contact assembly 16 at its radially inner end. Cooperating with each stationary contact assembly is a movable contact 28 pivotally mounted upon a stationary pivot 29. These pivots 29 are supported upon stationary brackets 31 which are integral with one end of a stationary operating cylinder 32. Suitable means (not shown) are provided for transferring current between the movable contacts 28 and the brackets 31, so that the brackets 31 together with the cylinder 32 form a conductive path electrically interconnecting the two movable contacts 28.

The cylinder 32, at its left hand end, is suitably supported from a generally cylindrical housing 33, which, in turn, is suitably secured at its left hand end to the metallic casing 12. The mechanical connection between the housing 33 and the casing 12 is best shown in Fig. 4, where the housing 33 is shown provided with a flange 34 that is suitably joined to a flange 35 secured to the casing 12.

For producing a gas-blast action for extinguishing the arcs which are established by separation of the contacts 16 and 28, the housing 33 is provided with a normally-closed annular exhaust passage 36 which leads from the interrupting chamber 11 to the surrounding atmosphere. This will be more readily apparent from Fig. 4. The housing 33 at its right hand end is formed with a pair of generally diametrically-opposed nozzle-type electrodes 38 defining inlets to the exhaust passage 36. For controlling

the flow of arc-extinguishing gas through the nozzle electrodes 38 and through the exhaust passage 36, there is provided at the outer end of the exhaust passage 36 a cylindrically-shaped reciprocable blast valve member 40 which slides smoothly in a surrounding tubular valve housing 41 integrally formed in the housing 33. In Fig. 4, the valve member 40 is shown in its closed position wherein an annular flange 42 formed at its left hand end sealingly abuts against the stationary flange 34, which serves as a valve seat. The valve member 40 is normally maintained in this closed position of Fig. 4 by the action of a suitable spring (not shown) and by the action of the pressurized gas within the passageway 36. This gas produces upon the flange 42 an unbalanced force urging the valve member 40 to the left into its closed position.

Since the chamber 11 is normally filled with pressurized gas, it will be apparent that when the valve member 40 is opened by movement to the right (by means not shown), gas in the chamber 11 will flow at high speed through the nozzles 38 and out the passage 36 past valve member 40 to atmosphere, as is indicated by the arrows e and f shown in Fig. 4. This rapid flow of gas through the nozzles 38 creates an axial arc-enveloping blast which acts rapidly to extinguish the arcs which are drawn adjacent the nozzles by movement of the movable contacts 28 away from their stationary contact assemblies 16.

For operating the blast valve 40 and the movable contacts 28, a combined operating mechanism preferably of the fluid-actuated type shown in the aforementioned Beatty patent is provided within the cylinders 32 and 33. The details of this operating mechanism form no part of the present invention and, hence, such details are not shown in the present application. An adequate understanding of the present invention may be had if it is understood that the operating mechanism acts during an opening operation to drive a piston rod shown at 58 to the right and also acts to open the blast valve 40. The piston rod 58 is coupled to the contacts 28 (by means soon to be described) and, hence, such movement of the piston-rod serves to drive the contacts open. At a predetermined instant after the contacts 28 have been opened, the then-open blast valve 40 is driven closed by the operating mechanism, as is described in detail in the Beatty patent. This prevents further loss of gas from the interrupting chamber 11.

The means for coupling the piston rod 58 to the main contacts comprises a crosshead 59 and two sets of connecting links 60. The crosshead 59 is rigidly secured to the piston rod 58 by suitable clamping means, whereas the connecting links 60 are pivotally connected at 61 and 62 to the crosshead and movable contacts, respectively.

In the position of Fig. 1, the movable contacts 28 are biased into closed position by means of overcenter compression springs 64. Each of these springs 64 has one end pivotally supported at 65 on a projecting portion of one of the brackets 31. At their inner ends, the springs 64 are pivotally supported on the crosshead 59. These overcenter springs 64 tend to urge the contacts closed while the crosshead 59 is to the left of a reference line connecting the pivots 65. But when the crosshead is moved to the right beyond this reference line (as occurs during a contact-opening operation), the overcenter springs thereupon tend to urge the contacts in a contact-opening direction. This action coupled with that of the operating mechanism acts to hold the contacts 28 in a fully-open position until the operating mechanism is subsequently operated to close the contacts 28.

Shunting the upper pair of main contacts 16, 28 is an impedance element 70, preferably in the form of a resistor wound about an insulating core 70a carried by a conductive tube 71. The conductive tube 71 is supported from the conductive stud 20 by means of conductive webs 72 electrically interconnecting the tube 71 and the stationary contact assembly 16. The lower terminal of the resistor 70 is connected to the tube 71, whereas the upper terminal

is locally insulated from the tube 71 and is connected by means of a conductor 74 to an electrode 73 of an impedance or resistor switch 75.

The resistor switch 75 comprises, in addition to the electrode 73, a second electrode 76 spaced from electrode 73 and coacting with electrode 73 to form an interrupting gap between the two electrodes. The electrode 73 is supported on the central housing 33 by an insulator 77 which is capable of electrically isolating the electrode 73 from the housing 33 when the resistor switch is open. The electrode 73 is also supported on the housing 33 but is electrically connected to the housing. Electrically bridging the two stationary electrodes 73 and 76 is a movable electrode 78, which in its closed position of Fig. 1, butts against the two stationary electrodes. Thus, it will be seen that the resistor 70 is connected in shunt with the upper contacts 16, 28 by means of a circuit which extends through the parts 72, 71, 70, 74, 73, 78, 76 and 33. As will be apparent from Fig. 1, the lower main contacts 16, 28 are shunted by a similar circuit. Since the parts forming this lower shunting circuit are substantially identical to those forming the upper circuit, corresponding lower parts have been assigned corresponding reference numerals followed by the suffix "a."

The electrodes of the resistor switch may be thought of as being auxiliary contacts for the overall circuit breaker and are frequently referred to in the present application as "auxiliary contacts."

Referring more particularly to the resistor switch 75, it will be noted from Fig. 1 that each of the movable electrodes 78 and 78a has an elongated pin 80 integral therewith and projecting therefrom to the right. Each of these pins is freely received in an opening formed in a reciprocable cross-beam 81 of insulating material. A pair of compression springs 82 and 82a, each of which is disposed between the cross-beam 81 and one of the movable electrodes 78 or 78a, urges the movable electrodes into firm circuit-closing engagement with the stationary electrodes. While the switch 75 is in its normal closed position of Fig. 1, the cross-beam 81 is restrained from moving to the right, as will soon appear more clearly. When, however, the cross-beam 81 is driven to the right during a switch-opening operation, it eventually impacts against suitable abutments 83 adjustably secured to the outer ends of the pins 80 and, thus, drives the movable electrode 78 and 78a to the right into an open position spaced from the stationary electrodes. To aid in guiding the cross beam 81 during such opening movement, a suitable guide pin 84 is shown secured to a stationary portion of the switch 75 and projecting through a guide opening formed in the crossbeam.

Opening of the resistor switch 75 is precisely coordinated with opening of the main contacts 16, 28 by means including a switch-operating rod, or coordinating member, 85 which is suitably secured to the crosshead 59, as shown in Figs. 1. This securing means of Fig. 1 comprises a pair of nuts 86 threaded on the operating rod 85 and clamping a bracket 87 therebetween. The bracket 87 is bolted or otherwise secured to the crosshead 59.

As will be apparent from Figs. 1 and 2, the operating rod 85 extends from the crosshead 59, through an opening 89 in the cross-beam 81, into a cylinder 90 mounted on the casing 33 of the breaker. The opening 89 in the cross-beam 81 is large enough to permit the operating rod 85 to move freely relative to the cross-beam.

As shown in Fig. 2, the operating rod carries at its left hand end an abutment 91 which is preferably threaded thereon and is prevented from accidentally moving out of its position of adjustment by means of a suitable jam nut 92. Further to the right, a second abutment 93 is secured to the rod 85, and between this second abutment 93 and the cross-beam 81, a compression spring 94 is disposed. This compression spring 94 and the abutment 93 are disposed within a tubular housing 95 which is secured to the crossbeam 81 and is slidably

mounted within the cylinder 90 by means of suitable slide bearing 95a. The compression spring 94 urges the cross-beam 81 to the right toward its open position, but the cross-beam 81 is restrained in its position of Fig. 2 by the abutment 93. In this regard, as shown in Fig. 2, the abutment 93 bears against an internal shoulder of the tubular housing 95 and, thus, restrains the tubular housing 95 and hence the cross-beam 81 from moving to the right.

Coacting with the tubular housing 95 is a latch 96 which is shown pivotally mounted on the cylinder 90 by a stationary pivot pin 97. The latch 96 at its right hand end has a head 98 which is loosely received in a slot 99 formed in the tubular housing 95. A suitable spring, such as the torsion spring 100, urges the latch 96 counterclockwise about its pivot 97 into the position of Fig. 2, where its head 98 is seated within the slot 99.

When the operating rod 85 is driven to the right during a circuit-breaker opening operation, it drives the abutment 93 to the right thereby compressing the spring 94. During such movement of the operating rod 85 from its position of Fig. 2 to that of Fig. 3, the latch 96 blocks movement of the tubular housing 95 and the connected cross-beam 81, thus preventing the spring 94 from discharging at its right hand end during this interval. As the operating rod continues its rightward opening movement through the position of Fig. 3, the abutment 91 on the operating rod engages a cam surface 101 formed on the latch 96. This forces the latch 96 downward, thereby releasing it from latching relationship with the tubular housing 95.

When the latch 96 is so released, the charged spring 94 discharges thereby forcing the cross-beam 81 to the right. The springs 82 and 82a also discharge in response to latch release and thus aid in driving the cross-beam 81 to the right. The movable contacts 78, 78a remain closed until the cross-beam moves sufficiently to the right to engage the abutments 83, shown in Fig. 1. This impact coupled with continued motion of the cross-beam 81 to the right, simultaneously drives the electrodes 78, 78a to the right into an open-circuit position spaced from the stationary electrodes. Preferably, this opening travel of the electrodes 78 and 78a is approximately equal to the distance moved by the crosshead 59 after the main contact first part. Thus, at the end of the opening stroke, the shoulder 112 on tube 95 bears against abutment 93.

The arcs which are established by opening movement of the movable electrodes 78, 78a are quickly extinguished by blasts of fluid which flow at high speed through the arcing regions. To this end, the electrodes 76 and 76a are each formed of a hollow construction with centrally disposed blast passages 105 leading into the annular blast passage 36. When the blast valve 40 is opened, pressurized fluid flows at high speed through these blast passages, and the resulting blasts are capable of quickly extinguishing the arcs which are formed by opening movement of electrodes 78, 78a.

It is to be noted that the arc-extinguishing blasts through all of the circuit-interrupting arcs of the breaker are controlled by the single blast valve 40 located downstream from the arcs. When the opening operation is completed and the blast valve 40 has closed, the pressurized gas in the interrupting chamber 11 maintains a high dielectric strength insulating gap between each pair of spaced contacts, or electrodes, thus maintaining the circuit open.

The above-described operating mechanism for the resistor switch 75 is capable of consistently parting the electrodes of the switch at a precisely-controlled predetermined instant that is spaced by an interval of relatively great duration from the instant at which the main contacts 16, 28 part. With regard to the extensive duration of this time-delay, it is to be noted that the operating rod 85 effects release of the latch 101 after the main contacts open 16, 28 part and, preferably, near the end

of their opening stroke. Moreover, even then, the discharging spring 94 does not immediately open the electrodes 78, 78a but must first drive the cross-beam 81 through its relatively extensive lost-motion travel into engagement with the abutments 83 before the switch electrodes 78, 78a begin to part. With regard to precisely controlling this time-delay with a high degree of consistency, it is to be noted that operation of the switch is not significantly affected by temperature or pressure variations in the interrupting medium, inasmuch as this medium is not being relied upon as an actuating fluid, as in many prior constructions. Nor does the switch rely upon dashpots or similar timers, which are subject to varying characteristics as a result of temperature changes.

In the disclosed switch, the point of latch release is controlled positively from the actuating means (59) for the main contacts, and time-delay occurring thereafter depends almost entirely upon the inertia of the moving parts of the switch 75, since it is such inertia which primarily controls the rate at which the spring 94 drives the contact-actuating cross-beam 81. It is to be further noted that the electrodes of the resistor switch are of the butt-type substantially devoid of sliding engagement between the electrodes, thus avoiding significant variations in the frictional retarding forces imposed by the contacts during opening movement. In contrast, with sliding contacts, those irregularities in the contact surface resulting from arcing can introduce some relatively unpredictable retarding forces which could significantly affect the desired time delay. With butt contacts of the type present in the disclosed switch, such sliding friction is largely absent and therefore can introduce no objectionable variations in the duration of this time delay.

With regard to controlling the time-delay which occurs after the latch 96 is released, the effective mass of the cross-beam 81 is purposely made very large in comparison to that of the contact structure 78, 80, 83 and 78a, 80, 83. To this end, a relatively massive block 81a is suitably joined to the cross-beam 81 so as to retard initial discharge of the springs 82 and 94 to a predetermined desired extent. Since the combined mass of the cross-beam together with its attached block is much greater than that of the contact structure, once the springs 82, 94 have driven these parts 81 and 81a through their lost-motion travel, considerable momentum has been attained and the relatively light contacts 78, 78a can then be picked up without an objectionable reduction in opening speed. This allows the contacts 78 and 78a to open at the desired high speed in spite of the initial retardation of spring discharge.

Another feature of my switch is that it is an inexpensive and compact device having its major components housed within a slender cylinder 90 which is readily attachable to a stationary part of the switch. In this latter regard, note in Fig. 1 that suitable fastening devices in the form of conventional screws 110 are utilized to secure the switch 75 to the side of the circuit breaker casing 33.

Closing of the circuit breaker is effected by returning the cross-head 59 from its open position leftward to its closed position shown in Fig. 1. At the beginning of this closing stroke, the left end 112 of the tubular casing 95 is bearing against the abutment 93 and, accordingly, initial leftward movement of the crosshead 59 and the connected operated rod forces the tubular casing 95 together with the crossbeam 81 to the left, thus driving the electrodes 78, 78a toward closed position. Simultaneously with such action, leftward movement of the cross-head 59 is also driving the movable main contacts 28 closed. Since the distance between fully-open position and the point at which the contacts first touch is approximately the same (in terms of travel of crosshead 59) for both the main contacts and those of the resistor switch, the movable contact of each of these sets of con-

tacts first touches its stationary contact at roughly the same instant for each set of contacts.

While I have shown and described a particular embodiment of my invention, it will be obvious to those skilled in the art that various changes and modifications may be made without departing from my invention in its broader aspects and I, therefore, intend in the appended claims to cover all such changes and modifications as fall within the true spirit and scope of my invention.

What I claim as new and desire to secure by Letters Patent of the United States is:

1. In an electric circuit breaker, separable main contacts, impedance means shunting said main contacts, separable auxiliary contacts connected in series with said impedance means and in shunt with said main contacts, a common actuating member for a movable one of said main contacts and for a movable one of said auxiliary contacts, means for connecting said actuating member to said one main contact for parting said main contacts in response to opening movement of said actuating member, a reciprocable rod connected to said actuating member, a spring operatively connected between said movable auxiliary contact and said rod and arranged to be charged by movement of said rod during opening movement of said actuating member, latch means blocking discharge of said spring during initial opening movement of said actuating member, means controlled by said rod for releasing said latch means after a predetermined opening movement of said actuating member to allow said spring to discharge, and means responsive to discharge of said spring for driving said one auxiliary contact out of engagement with the other said auxiliary contacts at an instant appreciably after said main contacts have parted.

2. In an electric circuit breaker, separable main contacts, impedance means shunting said main contacts, separable auxiliary contacts connected in series with said impedance means and in shunt with said main contacts, a common actuating member for a movable one of said main contacts and for a movable one of said auxiliary contacts, means for connecting said actuating member to said one main contact for parting said main contacts in response to opening movement of said actuating member, a coordinating member connected to said actuating member, a spring operatively connected between said movable auxiliary contact and said coordinating member and arranged to be charged by movement of said coordinating member during opening movement of said actuating member, latch means blocking discharge of said spring during initial opening movement of said actuating member, means controlled by said coordinating member for releasing said latch means after a predetermined opening movement of said actuating member to allow said spring to discharge, a driven member coupled to said spring and arranged to be actuated by said discharge of said spring, coupling means forming a lost-motion connection between said driven member and said one auxiliary contact for permitting said spring, in discharging, to drive said driven member through a predetermined travel before establishing a positive connection between said auxiliary contact and said driven member, said coupling means thereafter transmitting contact-separating forces to said auxiliary contact and parting said auxiliary contacts appreciably after said main contacts have been parted, the effective mass of the structure driven by said spring prior to establishment of said positive connection being substantially greater than the effective mass of the added structure driven by said spring after establishment of said positive connection.

3. In an electric circuit breaker, separable main contacts, impedance means shunting said main contacts, separable auxiliary contacts of the non-sliding butt-type connected in series with said impedance means and in shunt with said main contacts, a common actuating member for a movable one of said main contacts and for a movable one of said auxiliary contacts, means for

connecting said actuating member to said one main contact for parting said main contacts in response to opening movement of said actuating member, a coordinating member connected to said actuating member, a spring operatively connected between said movable auxiliary contact and said coordinating member and arranged to be charged by movement of said coordinating member during opening movement of said actuating member, latch means blocking discharge of said spring during initial opening movement of said actuating member, means controlled by said coordinating member for releasing said latch means after a predetermined opening movement of said actuating member to allow said spring to discharge, a driven member coupled to said spring and arranged to be actuated by said discharge of said spring, coupling means forming a lost-motion connection between said driven member and said one auxiliary contact for permitting said spring, in discharging, to drive said driven member through a predetermined travel before establishing a positive connection between said auxiliary contact and said driven member, said coupling means thereafter transmitting contact-separating forces to said one contact and parting said auxiliary contacts appreciably after said main contacts have been parted.

4. The circuit breaker of claim 3 in combination with additional spring means connected between said driven member and said movable auxiliary contact for maintaining said movable auxiliary contact closed during movement of said driven member through said predetermined travel.

5. In an electric circuit breaker of the fluid-blast type, separable main contacts, impedance means shunting said main contacts, separable auxiliary contacts connected in series with said impedance means and in shunt with said main contacts, blast valve means located downstream from said contacts and openable to produce an arc-extinguishing blast of fluid through the region of said contacts when said contacts are being opened during a circuit-interrupting operation, a common actuating member for a movable one of said main contacts and for a movable one of said auxiliary contacts, means connecting said actuating member to said one main contact for parting said main contacts in response to opening movement of said actuating member, a reciprocable rod connected to said actuating member, a spring operatively connected between said movable auxiliary contact and said rod and arranged to be charged by movement of said rod during opening movement of said actuating member, latch means for blocking discharge of said spring during initial opening movement of said actuating member, means controlled by said rod for releasing said latch means after a predetermined opening movement of said actuating member to allow said spring to discharge, and means responsive to discharge of said spring for driving said one auxiliary contact out of engagement with the other said auxiliary contacts at an instant appreciably after said main contacts have parted.

6. In an electric circuit breaker, separable main contacts, impedance means shunting said main contacts, separable auxiliary contacts connected in series with said impedance means and in shunt with said main contacts, a common actuating member for a movable one of said main contacts and for a movable one of said auxiliary contacts, means for connecting said actuating member to said one main contact for parting said main contacts in response to opening movement of said actuating member, a reciprocable rod connected to said actuating member, a cylindrical member in which said rod is movable, a tubular casing surrounding said rod and disposed within said cylindrical member, abutment means secured to said rod and disposed within tubular casing, a driven member secured to said tubular casing and coupled to said contacts, a spring disposed within said tubular casing and operatively connected between said abutment means and said driven member, latch means for blocking

discharge of said spring during initial opening movement of said actuating member, means controlled by said rod for releasing said latch means after a predetermined opening movement of said actuating member, and means responsive to discharge of said spring for driving said one auxiliary contact out of engagement with the other of said auxiliary contacts at an instant appreciably after said main contacts have parted.
